UNITED STATES PATENT OFFICE.

LESLIE R. COFFIN, OF LOS ANGELES, CALIFORNIA.

MACHINE FOR MOLDING BUILDING TILES.

Application filed January 2, 1924. Serial No. 683,955.

This invention relates to a machine for molding building tiles and is more particularly directed to a machine for molding hollow gypsum fireproof wall or partition tiles, using metallic cores.

In the art of molding fireproof wall tiles great difficulty has been encountered in removing the cores from the blocks after the blocks have set in the molding machine; due to the adhesion of the material used to the cores. A great loss in efficiency results from the methods heretofore used because of the breaking and damaging of tiles or blocks during the process of removal of the cores therefrom and in the removing of the tiles or blocks from the machine. Wooden cores were first used in this art, and proved very unsatisfactory. Aluminum cores then replaced the wooden cores, and while this invention relates to a machine employing aluminum cores or cores of metallic alloys that resemble aluminum, the use of aluminum cores is not claimed as a part of the invention.

An object of this invention is to provide a machine employing cores of aluminum or metallic alloys resembling aluminum in which the cores may be easily and efficiently removed from the blocks without damaging the blocks.

An object of this invention is to provide a machine in which the molding cores are held rigidly and the molded tiles or blocks moved from engagement therewith.

An object of this invention is to provide a mechanism wherein the maximum withdrawal force is applied at the start of the withdrawal of blocks from the cores.

An object of this invention is to provide a mechanism wherein the force applied to remove the tile from the cores diminishes as the tiles proceed from the cores.

An object of this invention is to provide a machine for molding a multiplicity of fireproof building blocks in one operation, said tiles to be separately disposed in the machine and easily removable therefrom.

An object of this invention is to provide a machine having the above enumerated advantages that is manually operated and requires a minimum of labor.

Other objects and advantages will be apparent from the following detailed descrip-

tion of a preferred embodiment of this invention, of which the accompanying drawings are a part.

In the drawings:

Figure 1 is a plan view of a machine embodying this invention.

Fig. 2 is a side elevation thereof.

Fig. 3 is a plan view partly broken away, taken substantially on the line 3-3 of Figure 1, showing the gypsum blocks as molded in this machine, illustrating a construction of the pivoted side plates.

Fig. 4 is a side elevation partly in section illustrating the fastening and position of the cores.

Fig. 5 is a sectional side view showing the construction of the car guide plates embodied in this invention.

Fig. 6 is a view taken substantially on line 6-6 of Figure 2, showing the car guides.

In the drawing, 1 generally indicates the frame of the car, which has channel iron supports 2. Bearings 4 are fixed to the channel irons 2 and are adapted to carry the axle 6 to which the wheels 7 are journaled. 8 illustrates frame members extending rearwardly, to which an axle 9 is journaled in suitable bearings 10 supporting a rear wheel 11. The wheels 7 and 11 are positioned to run on the tracks 12 which are rigidly connected by cross members 13, rigidly secured by the angle irons 14.

The back plate 15 is secured to the tracks 12, as shown at 16, and is held in vertical position by the reinforcing members 17. Tapered aluminum cores 18 are bolted to the back plate by bolts 19. The bolt holes 20 are of greater diameter than the bolts 19 to allow the cores to be adjusted in their correct position on the back plate 15.

A shaft 22 is journaled in suitable bearings in the reinforcing members 17. Keyed to the said shaft are the eccentric wheels 23 having diverging arms 24 cast to the said wheels 23 and forming an eccentric rod shoulder 25, having an arm hole 26 through which an eccentric rod 27 projects; the length of the rod 27 is regulated by means of the nuts 28 which are screwed on the rod as shown in Figure 2 of the drawings.

On the other end of the rods 27 are eccentric arm grips 29 adapted to fit closely a

square rod 30, which rod 30 runs transversely through the wheeled car.

The rod 30 is secured in the car side plate 31 and projects from each side thereof to be engaged by eccentric arm grips 29.

The eccentric rod 27 is made adjustable in length so as to establish the greatest torque exerted to move the car from the back plate at the start of the rearward motion of the car. The above mentioned torque is produced by exerting a force on eccentric actuating arms 32, which arms 32 are rigidly secured to the eccentric wheels 23 as shown at 33.

15 Arms 50 are secured to the eccentric wheels 23 so that when the eccentric actuating arms 32 are pushed down and have moved the car away from the back plate 15, the shoulders 51 of the arms 50 engage the eccentric rods 27 and lift the jaws 29 from engagement with the rod 30.

Secured to the car frame 1 is the car base plate 34, and car side plates 31, to which side plates 31 a top plate 35 is hinged or otherwise secured.

20 Pivoted on shafts 36 are block side plates 37; transverse spacing plates 38 are riveted to the plates 37. A plate 39 located approximately on the center of the car is rigidly secured to the car and provided with a pair of transverse spacing members 40.

25 Securely riveted to the back plate 15 are curved angle iron plates 41 which form guideways and clamps to position the mold walls formed by the members 37 and 38.

30 Securely riveted to the plate 15, positioned so as to engage the frame of the car, are angle guides 43, said guides 43 to extend further to the rear than the plates 41 to correctly position and square the car in relation to the back plate 15 before the angle plates 41 clamp the members 37 in position.

35 The operation of this preferred embodiment of my invention is:—

40 The car is run forward on the tracks 12 to a position that allows the eccentric arm jaws 29 to engage the square rod 30 at each end of the said rod 30. The eccentric actuating arm is then pushed downward forcing the car forward to engage the guides 43, which results in correctly positioning the car on the track in relation to the back plate 15. The end side plates 37 then engage the curved angle iron plates 41, which plates 41 have a cam action, forcing the plates 37 together and locking the same in their correct position in relation to the cores.

45 The machine is then in position for the molding of the blocks. A hopper containing fireproof material (preferably gypsum) is then run over the machine above the cores and the material poured around the cores in the spaces formed by the side plates 37, the plates 38 and the back plate 15. The molding material is then allowed to set. After

the blocks have hardened the eccentric actuating arms are forced upward, which results in pushing the car back, disengaging the blocks from the cores. The blocks having been released from their bond with the cores, 70 it is an easy matter to push the cars further backward to completely move the blocks from the cores.

The pivoted side plates are then pushed to the side, which action results in releasing the blocks from their bond with the said side plates 37. The blocks are then picked from the machine and taken to a drying chamber or exposed to the drying action of the sun. The machine is then ready to mold another 80 set of blocks.

I prefer to treat the plates 37, 38, back plate 15, and the cores with a mixture of kerosene and paraffin prior to this molding, as this treatment allows a quicker and more 85 efficient removal of the molded blocks from the machine.

Having fully described a preferred embodiment of this invention and the use thereof, it is to be understood that I do not 90 wish to limit myself to the construction disclosed, which may be varied in detail without departing from the spirit of the invention as pointed out in the following claims.

I claim:—

1. In a machine for molding building blocks, the combination of a car, comprising pivotal members forming molding zones, a stationary plate, cores secured to the stationary plate, and guide members secured to 100 said stationary plate, guiding said car into engagement with said plate.

2. In a machine for molding building blocks, the combination of a car running on a track, said car comprising molding zones having pivotal sides, a stationary plate, and means engaging the car with the plate. 105

3. In a machine for molding building blocks, the combination of a car comprising pivotal members forming molding zones, a 110 stationary plate, cores secured to the stationary plate, means to force said car to engage said plate, and guide members clamping said pivotal members in rigid contact.

4. In a machine for molding building blocks, the combination of a car, comprising pivotal members forming molding zones, and a stationary plate member secured to tracks on which said car is adapted to run. 115

5. In a machine for molding building blocks, the combination of a car, comprising side members, pivotal members forming molding zones, a rod secured to said side members, a stationary plate to which cores are secured, members reinforcing the stationary plate, a shaft journaled in the reinforcing members, eccentric wheels secured to said shaft, adjustable eccentric arms secured at one end to said wheels, jaws on the other end of said arms adapted to engage 125 120 130 135 140 145 150 155 160 165 170 175 180

said rod, and means to rotate said eccentric wheels to force said car to engage the stationary plate.

6. In a machine for molding building blocks, the combination of means to support a plurality of sets of cores, and a plurality of pivoted side plates pivoted outwardly from a central stationary plate and forming with the central plate molding zones adapted 10 to receive gypsum for the production of cored building blocks and means for holding the pivoted side plates from swinging inward toward the center plate.

7. In a machine for molding building blocks, the combination of a molding box comprising a stationary central plate, pivotal members mounted on the opposite sides of the stationary plate and adapted to

swing away from the central plate, and means for holding the pivotal members from 20 swinging inwardly toward the central plate.

8. In a machine for molding building blocks the combination of a stationary plate, pivotal side plate adapted to swing away from the said stationary plate means for 25 preventing the pivotal plate from swinging inward toward the stationary plate beyond a position parallel with the stationary plate, an end plate, a plurality of cores supported on the end plate and means for positioning 30 the cores within the space between the stationary plate and the pivotal plate.

Signed at Los Angeles, California, this 27th day of December, 1923.

LESLIE R. COFFIN.
